WASTE RECEPTACLE

Abraham Singer Karper, New York, N. Y.

Application June 3, 1933, Serial No. 674,195

5 Claims. (Cl. 220—36)

This invention relates to improvements in waste receptacles, and particularly to the type designed to afford a safe and sanitary depository for material which, because of odor or for other reasons, is deemed objectionable.

It is an object of the invention to provide an article of this character which is substantially air-tight when in closed position and yet opens readily with a minimum of effort, rendering accessible the waste-receiving portion thereof.

A further object is that of providing a receptacle in which the cover, when in open position, is shifted away from any danger of being soiled when waste is deposited within the receptacle.

Another object is that of providing an article of this type which is extremely flexible in its adaptation and renders itself available for many uses.

Still another object is that of providing a waste receptacle which has the maximum capacity while occupying a minimum of space, and which is at the same time pleasing in appearance.

With these and other objects in mind, reference is had to the attached sheets of drawings, and in which:

Fig. 1 represents a cross-sectional view, taken along the line 1—1 of Fig. 2, of one form of receptacle with an inner waste-receiver in position;

Fig. 2 is a front elevation of the same receptacle showing the side door of the receptacle in retracted position so that the inner waste-receiver may be removed;

Fig. 3 is a plan view of the receptacle shown in Figs. 1 and 2, taken along the line 3—3 of Fig. 2, with the inner waste-receiver removed and showing the mounting of the retractable side door of the receptacle;

Fig. 4 is an enlarged view of a portion of the operating mechanism which actuates the cover of the receptacle shown in Figs. 1 through 3;

Fig. 5 is a cross sectional plan view of another form of container embodying a retractable side door opening;

Fig. 6 is a composite side elevation of two forms of receptacle, the one being constructed without an inner waste-receiver;

Fig. 7 is a partially broken away front elevation of a still further form of receptacle, showing a different type of operating mechanism;

Fig. 8 is an enlarged view of a portion of the operating mechanism used in connection with the receptacle shown in Fig. 7; and

Fig. 9 is a fragment of a receptacle in cross

section, showing a still further modification of the cover-actuating mechanism.

Referring now primarily to Figs. 1 through 4 we have a receptacle formed with a semi-circular forward wall 10 and a flat rear wall 11 so that in appearance the receptacle resembles half of a conventional cylindrical can. The receptacle is provided with a base 12 and a retractable side door 13 which is mounted by means of a supporting member 14 which, in turn, is pivoted at 15 to a bracket 16 carried by the rear wall of the receptacle. The door likewise is guided in its movement by means of a rail member 17 positioned directly behind the front wall of the receptacle and which provides a groove or track-way for the top of the door 18 to travel in. The door is also provided with a handle member 19 with which it is readily moved from open to shut position. The receptacle base is mounted at its forward edge to the front wall of the receptacle 20 by means of a bracket 20, rubber or similarly covered, which additionally acts as a stop member to limit the extent of travel of the member 14, thus preventing the door from being opened too far. The upper portion of the front wall of the receptacle is curved inwardly at 21 and has a shoulder 22 at its upper edge. A receptacle cover 23 in the form of a segment of a hemisphere is mounted by means of a supporting arm 24 which is pivotally secured to the walls of the receptacle at 25. A handle 23a is secured to the cover so that it may be opened by hand, if desired. In place of the handle 23a a rail member might be formed, extending across the upper edge of the cover so that the user could open the cover from any position. The cover is also formed with a bead 26 at its lower edge which strikes against a cushioning member 27 of rubber or other suitable material which is secured to the under side of the shoulder 22, thus noiselessly limiting further upward movement of the cover.

The rear wall of the receptacle is likewise provided with a shoulder 28 under which the top or forward edge of the cover projects, and a rubber or other bead member 28a is fastened to the under side of the shoulder, thus affording a seal at this point for the parts. It will be noted that the cover is so proportioned that it does not strike against the rear wall 11 of the container but is arrested in its movement just short of this point by the engagement of the bead 26 with the cushioning member 27.

Extending from the supporting arm at right angles thereto adjacent the point of pivot of

55

the arm, is a bell crank lever 29 which has coupled to its outer end a spring 30. The free end of the spring is fastened to the pivot mounting 31 which is, in turn, secured to the rear wall of the receptacle. Likewise, pivotally secured to the outer end of the bell crank lever at 32 is a pull rod 33 which extends downwardly to a point adjacent the base of the receptacle, where it has secured to it a foot pedal 34. The 10 pedal extends rearwardly and is pivoted to the base of the can at 34a and to the connecting link of the pull rod at 34b. The link, in turn, extends outside the receptacle through an opening 35 formed in the side wall thereof. In operation, the foot pedal 34 is depressed, carrying with it the pull rod 33 which, in turn, causes the bell crank lever 29 and the supporting arm 24 to pivot at 25, carrying with them the cover 23, so that it assumes the position shown by the 20 dotted lines in Fig. 1.

It is to be noted that by spacing the horizontal radius 36 of the cover vertically with respect to the point of pivot of the supporting arm 25, the cover is maintained, when in open 25 position, at a point where the bead 26 projects inwardly only to a slight degree from the vertical plane in which it is positioned when the cover is closed. Thus, the full interior of the receptacle is available to the user with a minimum 30 danger of soiling or contaminating the inside of the cover member. After the waste material has been deposited into the inner waste receiver 37, which may be of any well known construction, the foot is removed from the pedal 34, which 35 raises the bell crank lever 29, thus bringing the cover back to closed position.

Referring to Fig. 5, there is disclosed a cylindrical type of receptacle having an outside wall 80 in the form of a semi-circle, and a complementary inner side wall member 81 to complete the cylinder. A base ring 82 is secured to the outer side wall, and extending across the bottom thereof is a supporting strap 83 which is riveted, at 84 to the ring. This strap is formed with a pivot or bearing opening 85 in its center. Secured to the lower edge of the inner side wall is a cylindrical platform 86 which carries a pivot member 87 for cooperation with the pivot opening before mentioned. An inner receptacle of 50 any desired character is placed on this platform, which rotates about its point of pivot, causing the inner wall 81 to telescope with respect to the outer wall 80. A handle member 88 may be secured to the one edge of the inner wall to 55 facilitate opening and closing the same. The pedal 89 is pivoted to the base ring at 90 and is secured to the pull rod 91 at 92. This pull rod extends upwardly along the outside of the receptacle and is coupled to a cover mechanism, as already described in connection with Figs. 1 through 3. In a cylindrical receptacle, it is apparent that a plurality of cover portions might be provided all opening simultaneously by means of one actuating lever, or independently of each other by the provision of independent actuating levers. Likewise, a plurality of inner containers or waste receivers might be provided, one for each of the cover portions.

In Fig. 6 we find a modification of the receptacle in which there is provided a cylindrical receptacle with a side wall 50 and two independent cover members 51 which are spaced at the center by means of a partition 51a, which extends above the uppermost limit of the cover 75 portions and has a handle aperture 51b at that

point. This partition, in turn, may be utilized in securing the receptacle to a wall 52, so that, for example, a receptacle might be placed in an opening cut in the common wall of two rooms or compartments, and one-half would be accessible to the occupant of each room or compartment. Likewise, as shown in Fig. 6, the foot pedal might be in the form of a continuous rail member 53 extending halfway around the receptacle, so that it might be operated from any 10 position with respect thereto. As shown in the broken away portion of Fig. 6, instead of providing an inner waste receiver, the receptacle might be formed with a base 54 upon which is positioned the receptacle proper 55, which is a 15 complete can unit formed with its rear wall slightly lower than the forward wall, as at 56. Cooperating therewith is a shoulder 57 of the nonmovable portion of the cover 58, which shoulder provides for a seal between the cover 20 and the receptacle. A movable cover 59 would also be provided and would operate in the usual manner.

Referring now to Figs. 7 and 8, we have a receptacle formed with a base 60 and side wall 25 members 61 which are hinged at 62 to form door portions opening outwardly to allow access to the interior of the receptacle. These door portions have handles 63 to facilitate their opening. The cover 64 is supported, as heretofore described, by means of a supporting arm 65, which, in turn, is pivoted at 66 to a bracket 67, secured to the frame of the receptacle. A bell crank lever 68 is secured to the lower end of the supporting arm adjacent the point of pivot, 30 and a pull rod 69 extends downwardly to the foot pedal 70. Pivoted to the rear wall of the receptacle at 71 is an arm 72 which engages, at its free end, the bell crank lever 68 and which carries at its other end, a weight 73. In operation, it will be noted that by depressing the foot 40 pedal 70 and carrying with it the pull rod 69, the bell crank lever and supporting arm will be pivoted about the point 66 opening the cover member. As the bell crank lever moves downwardly, it will carry with it the arm 72, thus causing it, in turn, to pivot at 71 and raise the weight 73 which is carried at its other end. As soon as the foot is removed from the pedal 70, the weight 73 will immediately tend to move 50 downwardly, causing the rod 72 again to pivot at 71 and to engage the under side of the bell crank lever 69 and raise it upwardly, thus returning the cover to its closed position. If desired, the bell crank lever 68 and the arm 72 55 may be directly coupled to each other in a well known manner.

As shown in Fig. 9, the counter-balance actuating mechanism for the cover might be arranged so that the supporting arm 100 is pivoted 60 at 101 to the frame of the receptacle which is formed by the rearwardly extending arm 102, to which is supported a weight 103. When the cover 104 is lowered, either by means of a handle or a foot-actuated mechanism of the type heretofore disclosed, the arm 102 and the weight are raised, and when pressure is released from the cover, the weight tends to return to its initial position, carrying with it the cover. A well or shaftway 105 is provided for the weight, so that it will be protected from outside interference. This well is formed by adding a false rear wall 106 to the receptacle.

It will, of course, be apparent that the invention herein described might be carried out 75

with equal success in a container or receptacle of any desired shape, and the applicant does not wish to be restricted to the particular forms illustrated, but desires that all matter contained in the above description, or shown in the accompanying drawings, shall be interpreted as illustrative and not in a limiting sense. Likewise, many changes in construction and rearrangements of the parts might be resorted to without in the slightest departing from the spirit of the invention.

Having described my invention, what I claim as new and desire to secure by Letters Patent is:

1. A waste receptacle comprising a body portion, a cover portion, a frame pivotally secured to said body portion and supporting said cover, the point of pivot of said frame defining the center of a circle through an arc of which said cover moves from closed to open position, and the bottom edge of said cover being spaced from and above said pivot when the cover is in closed position.

2. A waste receptacle comprising a body portion, a cover associated therewith and adapted to swing through the arc of a circle from open to closed position, and supporting means disposed within said receptacle and pivotally connecting said cover to said body portion, the lower edge of said cover being spaced from and above the pivot of said supporting means when the cover is in closed position.

3. A waste receptacle comprising a body portion, a cover for association therewith and de-

fining a section of a sphere, supporting means to secure said cover to said body portion in pivotal relationship, the lower edge of said cover being spaced from and above the point of pivot of said supporting means when the cover is in closed position and a wall forming a part of said receptacle, the upper edge of said cover, in the movement of the latter towards closed position, shifting upwardly and rearwardly into movement arresting contact with the face of said wall.

4. A container including a body formed with an opening, a cover for closing such opening, said cover presenting an inner edge portion, extensions projecting inwardly and beyond such edge portion and pivotally connected to said body whereby to rockingly support said cover with respect thereto, and a lever secured to one of said extensions and projecting angularly from the point of pivotal connection thereof whereby, through said lever, said cover may be shifted with respect to said body.

5. A container including a body formed with an opening, said body housing a receptacle and a cover for closing such opening and movably supported by said body, means whereby said cover may be shifted to allow access through said opening and to the receptacle enclosed within such body, and said cover in such open position acting as a guide to divert substances introduced towards the opening in said receptacle.

ABRAHAM SINGER KARPER.
